(57) **CLAIM**

The ornamental design for an utility knife, as shown and described.

DESCRIPTION

FIG. 1 is a first perspective view of an utility knife showing my new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof;

FIG. 9 is a perspective view of the utility knife, wherein the blade holder mechanism is shown in the open state; and, FIG. 10 is an enlarged view of the selected portion 10 in FIG. 1.

The broken lines shown in the drawings depict portions of the utility knife that form no part of the claimed design.
